UNITED STATES PATENT OFFICE

169,094

CONTAINER FOR GAME COUNTERS

Donald T. Paddock, Chicago, Ill.

Application October 15, 1952, Serial No. 21,830

Term of patent 14 years

(Cl. D34—13)

To all whom it may concern:

Be it known that I, Donald T. Paddock, a citizen of the United States, residing at Chicago, county of Cook, and State of Illinois, have invented a new, original, and ornamental Design for a Container for Game Counters, of which the following is a specification, reference being had to the accompanying drawings, forming a part thereof, in which:

Fig. 1 is a plan view of a container embodying my new design;

Fig. 2 is a side elevational view;

Fig. 3 is a side elevational view of the bottom portion of the container;

Fig. 4 is a top plan view of the bottom portion; and

Fig. 5 is a perspective view of the bottom portion of the container.

The top and bottom portions of the container are alike and fit together to form a closed container, and a plurality of containers may be nested one upon the other.

I claim:

The ornamental design for a container for game counters, as shown and described.

DONALD T. PADDOCK.
